UNITED STATES PATENT OFFICE.

HAYNES L. THOMAS, OF BRUNSWICK, GEORGIA.

SAW SET.

Application filed September 19, 1921. Serial No. 501,685.

To all whom it may concern:

Be it known that I, HAYNES L. THOMAS, a citizen of the United States, residing at Brunswick, in the county of Glynn and State 5 of Georgia, have invented certain new and useful Improvements in a Saw Set; and I do hereby declare the following to be a full, clear, and exact description of the invention, such as will enable others skilled in the art 10 to which it appertains to make and use the same.

The object of the invention is to provide a simple and efficient saw setting apparatus particularly designed and adapted for use 15 in connection with circular saws of relatively small diameter which are difficult to set with the conventional forms of setting devices by reason of the diameter thereof and the inadequacy of means ordinarily provided for 20 supporting the saw in proper position with relation to the setting anvil and plunger or hammer; and with this object in view the invention consists in a construction and combination of parts of which a preferred embodiment is shown in the drawing, wherein:

Figure 1 is a side view, and

Figure 2 is a plan view of an apparatus embodying the invention.

Figure 3 is a longitudinal central sectional 30 view of the same.

Figure 4 is a transverse section of the plunger or hammer guide on the plane indicated by the line 4—4 of Figure 1.

Figure 5 is a similar view of the anvil 35 carrying member on the plane indicated by the line 5—5 of Figure 1.

Figure 6 is a detail view of the gage lever by which the angular or rotary adjustment of the anvil and hammer or plunger is 40 accomplished.

Figures 7 and 8 are respectively view of the hammer or plunger and the anvil.

The base 10 which forms a guide or track for the bearing block 11 adapted for actuation 45 by a longitudinally disposed feed screw 12 having a terminal crank 13, is provided at one end with a substantial pedestal 14, intermediately cut away to form a recess 15 constituting a space between upper 50 and lower jaws 16 and 17 which are vertically bored in communication with the recess to form a guide 18 for the depressible hammer or plunger 19 and a socket 20 for the reception of the anvil 21, said plunger 55 and anvil consisting of preferably round bars having their adjacent extremities pro-

vided with complementary beveled setting faces arranged at a suitable angle for setting the teeth of a saw.

The upper side of the bearing block 11 is 60 substantially in the plane of the upper end of the anvil bar and is provided with a conical seat 22 for the reception of the conical journal block 23 adapted to be fitted into the shaft or arbor opening 24 of a circular saw 25, said journal block being mounted upon a pin 26 rising from the bottom of the bearing block at the center of the conical seat therein and having a collar 27 in which is mounted a thumb screw for adjustment 65 into terminal engagement with the pin 26 to lock the journal block at the desired adjustment, said journal block being designed to exert a frictional resistance upon the saw 70 blade to limit the rotary movement thereof 75 and hold it in proper position for the operation of the anvil and plunger upon its teeth.

Fitted upon the hammer or plunger is a collar 29 between which and the upper end 80 of the jaw 16 is arranged a spring 30 designed to yieldingly hold the plunger in its elevated position and therefore with its lower terminal die face out of contact with the face of the anvil to permit of the arrangement successively of the teeth of the saw between said faces for the setting operation. The upward movement of the plunger is limited by the contact of said collar 29 with a stop ring 31 supported by 85 arms 32 which are arranged in contact with opposite sides of the upper jaw of the pedestal and are slotted as at 33 for engagement by the set screws 34 to the end that the stop ring may be adjusted to vary the extent of 90 throw or vertical movement of the plunger.

In connection with the above described features there is employed a gage lever 35 having spaced plates 36 of which the outer or remote sides are in contact respectively 100 with the facing surfaces of the jaws 16 and 17, said plates being keyed to the plunger and anvil so that by a swinging movement of the lever of which the operating arm extends laterally from the pedestal, the anvil and plunger may be rotated or adjusted 105 angularly in their seats to a corresponding extent in any direction to dispose the operative, beveled or guide faces thereof in the desired relation to the teeth of the saw to 110 be set. In the construction illustrated the eyes of the gage lever are provided with

keys 37 to engage grooves 38 and 39 in the plunger and anvil bar, and in order to lock the parts in their adjusted positions suited to the saw which is to be set a set screw 40 is fitted into a suitable lateral opening in the lower jaw of the pedestal for terminal and locking engagement with the anvil bar as shown in Figure 5.

In practice after the alternate teeth of the saw have been set with one adjustment of the parts, it being obvious that the upper exposed end of the hammer or plunger bar may be struck by suitable implements to force the guide face thereof into sufficiently forcible operative relation with the anvil to set said teeth, the gage lever may be reversed in position to extend from the opposite side from the pedestal in an adjustment at the corresponding angle to effect the setting of the intermediate teeth to correspond with the previously set alternate teeth. The bifurcated or looped construction of the gage lever, with the eyes formed at the free ends of the side arms thereof provides a proper clearance for the saw blade to reach the proper position in relation to the anvil and plunger.

Having thus described the invention, what I claim is:—

30. 1. A saw setting apparatus having, in connection with saw supporting means, a pedestal provided with spaced jaws, plunger and anvil elements rotatably mounted in seats in said jaws with their operative faces exposed in the interval therebetween, the plunger element being reciprocable to bring its operative face into operative relation with the anvil, and means for simultaneously and correspondingly turning said anvil and plunger element to vary the relation of the operative or die faces thereof with reference to the saw supporting medium.

45. 2. A saw setting apparatus having, in connection with saw supporting means, a pedestal provided with spaced jaws, plunger and anvil elements rotatably mounted in seats in said jaws with their operative faces exposed in the interval therebetween, the plunger element being reciprocable to bring its guide face into operative relation with the anvil, and means for simultaneously and correspondingly turning said anvil and plunger elements to vary the relation of the operative or guide faces thereof with reference to the saw supporting medium, and consisting of a lever having spaced eyes keyed respectively to said plunger and anvil elements.

60. 3. A saw setting apparatus having, in connection with saw supporting means, a pedestal provided with spaced jaws, plunger and anvil elements rotatably mounted in seats in said jaws with their operative faces exposed in the interval therebetween, the

plunger element being reciprocable to bring its guide face into operative relation with the anvil, and means for simultaneously and correspondingly turning said anvil and plunger element to vary the relation of the operative or guide faces thereof with reference to the saw supporting medium, yielding means being provided for retracting the plunger element. 70

4. A saw setting apparatus having, in connection with saw supporting means, a pedestal provided with spaced jaws, plunger and anvil elements rotatably mounted in seats in said jaws with their operative faces exposed in the interval therebetween, the plunger element being reciprocable to bring its operative face into operative relation with the anvil, and means for simultaneously and correspondingly turning said anvil and plunger element to vary the relation of the operative or guide faces thereof with reference to the saw supporting medium, a spring for retracting the plunger element and stop mechanism for limiting the return movement of the plunger element and consisting of a ring arranged in the path of a collar on the plunger element and means for adjusting the ring parallel with the path of movement of the plunger. 75

5. A saw setting apparatus having, in connection with saw supporting means, a pedestal provided with spaced jaws, plunger and anvil elements rotatably mounted in seats in said jaws with their operative faces exposed in the interval therebetween, the plunger element being reciprocable to bring its guide face into operative relation with the anvil, and means for simultaneously and correspondingly turning said anvil and plunger element to vary the relation of the operative or guide faces thereof with reference to the saw supporting medium, and consisting of a lever having spaced eyes keyed respectively to said plunger and anvil elements, a set screw being employed for locking the anvil element in its adjusted positions. 100

6. A saw setting apparatus having saw positioning means, saw setting means including a coacting plunger and an anvil, means rotatably mounting said plunger and anvil, and an adjusting lever for said plunger and anvil having spaced plates one connected to the plunger and one connected to the anvil, the operation of the lever thus serving to vary the position of the plunger and anvil relatively to said saw positioning means. 105

In testimony whereof I affix my signature in presence of two witnesses. 110
